2,393,132

PRODUCTION OF ALKENYLPYRROLES

Cary R. Wagner, Utica, Ohio, assignor to Phillips
Petroleum Company, a corporation of Delaware

Application November 26, 1943, Serial No. 511,895

15 Claims. (Cl. 260—313)

The present invention relates to the production of alkenylpyrroles and, more particularly, to the production of vinylpyrrole by ethylation of pyrrole to produce ethylpyrrole and dehydrogenation of the resulting ethylpyrrole to vinylpyrrole. The invention also pertains to a continuous process for the production of vinylpyrrole from pyrrole and ethylene.

N-vinylpyrrole or 1-vinylpyrrole, as well as N-ethylpyrrole, or 1-ethylpyrrole, are known compounds. N-vinylpyrrole, which is reported to have a boiling point of 122° C., was prepared by the reaction of pyrrole with acetylene in the presence of potassium hydroxide at a temperature of 180° to 190° C. and a pressure of 20 atmospheres (Reppé and Keyssner, U. S. Patent No. 2,066,160; see also German Patent No. 618,120, British Patent No. 438,281 and French Patent No. 790,467). The only other reported method which is said to be capable of producing the compound comprises the reaction of pyrrole with a vinyl halide or ethylene halide in the presence of an alkaline compound (Reppé, Keyssner and Nicolai, U. S. Patent No. 2,153,993). The only other N-alkenylpyrrole which is reported is N-allylpyrrole or 1-allylpyrrole, which is stated to have a boiling point of 105° C. at a pressure of 48 millimeters of mercury. It was prepared by heating potassium pyrrole with allyl bromide in ether (Clamician and Dennstedt, Berichte, 1882, vol. 15, page 2581; Gazzetta chim. ital., 1883, vol. 13, page 17.)

Several C-alkenyl-substituted pyrroles have been reported. 2-allylpyrrole or alpha-allylpyrrole, which is stated to have a boiling point of 82° to 83° C. at a pressure of 24 millimeters of mercury, was prepared together with 2,5-diallylpyrrole by treatment of pyrrole magnesium bromide with allyl bromide in ether (Hess, Berichte, 1913, vol. 46, page 3127). On reduction of indolizine (pyrrocoline) with sodium and alcohol, 2-(1,3-butadienyl)-pyrrole was obtained. This product had a boiling point of 198° to 199° C. (Scholtz, Berichte, 1912, vol. 45, page 745).

N-ethylpyrrole or 1-ethylpyrrole has been obtained by heating potassium pyrrole with ethyl iodide (Ljubawin, Berichte, 1869, vol. 2, page 101; Bell, Berichte, 1878, vol. 11, page 1810; Zanetti, Gazzetta chim. ital., 1889, vol. 19, page 90; Berichte, 1889, vol. 22, page 660). It has been obtained by heating the ethylamine salts of mucic acid and saccharic acid, respectively (Bell, Berichte, 1876, vol. 9, page 936; ibid., 1877, vol. 10, page 1862; Bell and Lapper, Berichte, 1877, vol. 10, page 1962), and also by heating 1-ethylpyrrole-2-carboxylic acid by itself or with dilute

acids (Bell, Berichte, 1877, vol. 10, page 1862; Bell and Lapper, Berichte, 1877, vol. 10, page 1961). N-ethylpyrrole is reported to have a boiling point in the range of 129° to 131° C. Other N-alkyl-substituted pyrroles which are known are N-propylpyrrole and N-isoamylpyrrole, whose boiling points are 145.5° to 146.5° C. at a pressure of 755.8 mm. of mercury and 180° to 184° C., respectively.

10 C-alkyl-substituted pyrroles, in which the substituent is present on the carbon atoms of the ring, are also known and have been prepared and studied more extensively than the N-alkyl-substituted isomers. 2-ethylpyrrole or alpha-ethylpyrrole, for example, which is an oil having a boiling point of 163° to 166° C. at atmospheric pressure and 66° to 68° C. at a pressure of 17 to 18 mm. of mercury, was obtained by passing a mixture of vapors of pyrrole and ethyl alcohol over 15 zinc dust at 270° to 280° C. (Dennstedt, Berichte, 1890, vol. 23, page 2563). It has been obtained together with other products by heating potassium pyrrole with an excess of ethyl iodide (Clamician and Zanetti, Gazzetta chim. ital., 1889, vol. 19, page 90; Zanetti, Gazzetta chim. ital., 1889, vol. 19, page 290; ibid., 1891, vol. 211, page 248; Berichte, 1889, vol. 22, page 2517). 2-ethylpyrrole has also been obtained by treating a mixture of pyrrole and paraldehyde with zinc chloride and 20 subsequent heating of the reaction product (Dennstedt and Zimmermann, Berichte, 1886, vol. 19, page 2190). It has also been obtained by heating pyrrole magnesium bromide with ethyl iodide in ether (Oddo and Mameli, Gazzetta chim. ital., 1914, vol. 44I, 168), and with ethyl bromide in ether (Hess and Wissing, Berichte, 1914, vol. 47, page 1424; Hess, Wissing and Suchier, Berichte, 1915, vol. 48, page 1883).

25 N-alkyl-substituted pyrroles are readily isomerized to C-alkyl-substituted pyrroles by heat. This isomerization occurs at approximately 200° C. or higher. For example, N-methylpyrrole (1-methylpyrrole) is isomerized to 2-methylpyrrole (a C-methylpyrrole) by passing it through a tube heated until it glows weakly (Pictet, Berichte, 1904, vol. 37, page 2793). The change is from a compound of a lower boiling point to one of higher boiling point. In the process of my invention, a 30 preponderance of C-alkenyl-substituted pyrroles is believed to be formed generally, although the product of alkylation may be predominantly an N-alkyl-substituted pyrrole, depending upon the alkylation conditions.

35 It is an object of the present invention to pro-

vide an improved process for the production of 2-vinylpyrrole and its homologues and isomers.

A further object of the present invention is to provide a process for the production of alkenyl-pyrroles from olefins and pyrrole.

A further object of the invention is to provide a process for the production of alkyl-substituted pyrroles from an olefin and pyrrole and dehydrogenation of the alkyl-substituted pyrroles to alkyl-substituted pyrroles.

It is another object of the present invention to provide a continuous process for the production of alkenylpyrroles from olefins and pyrrole which involves the alkylation of pyrrole with an olefin and dehydrogenation of the resulting alkylpyrrole.

Other objects and advantages of the invention, some of which are referred to specifically hereinafter, will be apparent to those skilled in art to which the invention pertains.

According to the present invention, alkenylpyrroles are produced from pyrrole and an olefin by alkylation of pyrrole with an olefin and dehydrogenation of the resulting alkylpyrrole. 2-vinylpyrrole is produced, for example, by alkylation of pyrrole with ethylene to produce an ethylpyrrole, which is thereafter dehydrogenated to 2-vinylpyrrole. The process is preferably conducted in a continuous manner as hereinafter more specifically described. The alkylation is effected in the presence of catalysts whereas the dehydrogenation may be catalytic, which is preferred, or simply a noncatalytic thermal dehydrogenation.

One specific embodiment of the present invention, which consists of a continuous process for the production of 2-vinylpyrrole from pyrrole and ethylene, is represented diagrammatically on the accompanying drawing. In this process, ethylene and pyrrole are charged at suitable temperatures and pressures through conduit or line 1 to an alkylator 2. This alkylator contains a silica-alumina catalyst or other suitable alkylation catalyst. The pyrrole is charged in substantial excess over that which would be required for its complete monoalkylation by the ethylene charged.

The mixture after passing through alkylator 2 is then passed through conduit 3 to fractionator 4. Uncombined ethylene is discharged through vent 5 or is returned through conduit 6 to alkylator 2. In fractionator 4 a separation is also made between pyrrole, ethylpyrrole and any polyethylated pyrroles. The unethylated pyrrole passes back through line 6 to alkylator 2. Ethylpyrrole passes through conduit 7 to a furnace 8. Polyalkylated pyrroles, which accumulate at the bottom of fractionator 4, are recharged to alkylator 2, where they are partially dealkylated in the presence of the excess of pyrrole.

The ethylpyrrole is heated in furnace 8 to a suitable temperature for dehydration and is then passed through conduit 9 to a dehydrator 10 which is charged with a suitable dehydration catalyst. After being subjected to dehydrogenation, the product is passed through conduit 11 to a fractionator 12. In the event that noncatalytic dehydrogenation is to be used, dehydrator 10 is omitted and the desired thermal dehydrogenation is effected in furnace 8, which is a tube furnace, or other suitable pyrolysis apparatus, for example, a bath of lead or other molten metal, and the product is charged to fractionator 12.

Hydrogen and any low-boiling products which

are formed in the dehydrogenation may be discharged from the fractionator through vent 13. In the fractionator a separation is made between 2-vinylpyrrole, which is removed through a discharge outlet 15, and 2-ethylpyrrole, which is the overhead and is returned to furnace 8 through conduit 14 for further dehydrogenation.

To prevent polymerization of 2-vinylpyrrole during the distillation in fractionator 12, it is generally desirable to add an inhibitor such as sulfur to the material undergoing distillation. The inhibitor may be added at 16. If sulfur is used as inhibitor it will remain in the bottoms in fractionator 12 and will be discharged through conduit 15 with 2-vinyl pyrrole. For the purpose of removing the inhibitor in the 2-vinylpyrrole in conduit 15 a flash still 17 may be provided. The inhibitor is discharged through outlet 18 from flash still 17 and the overhead vinylpyrrole is recovered at outlet 19. Polymerized vinylpyrrole and higher-boiling residual materials may be charged through line 20 to furnace 8 for further pyrolysis. The recovered inhibitor, if relatively free from contaminants, may be reused by charging it to inlet 16 at the top of fractionator 12.

The foregoing process is typical and by suitable substitution may be used for the production of alkenylpyrroles generally from olefins and pyrrole.

Olefins which may be used for the alkylation to produce the corresponding alkyl-substituted pyrroles are ethylene, propylene, 1-butene, 2-butene, isobutylene (2-methyl-1-propene), pentenes, etc.

Instead of starting with pyrrole, substituted pyrroles may be used. For example, 3-methylpyrrole may be further alkylated with ethylene according to the process of the invention and then dehydrogenated to give 2-vinyl-3-methylpyrrole or some other isomer thereof. If one starts with a pyrrole substituted with an ethyl or higher alkyl group this group may be dehydrogenated in the subsequent dehydrogenation step.

Sulfur has been disclosed herein as an inhibitor of the polymerization of vinylpyrrole and other alkenylpyrroles. It may be used both in the distillation as described herein, being introduced at the top of fractionator 12, and to inhibit the polymerization of the product on storage, in which event its removal by distillation before use may be required. However, other polymerization inhibitors, for example, alkyl-substituted catechols and similar suitable alkyl-substituted phenols, may be used instead of or in conjunction with sulfur. The amount of inhibitor to be used is largely dependent upon the effectiveness of the inhibitor and upon the degree of inhibition that is desired. Normally, in distillation, to inhibit polymerization, an amount of sulfur within the range of 0.1 to 1 per cent by weight of the material in the column is generally sufficient, although more may be used if desired.

Instead of using a continuous process as described, the various operations may be performed in batchwise manner. Thus the various products may be condensed and reheated without relation to their utilization in a continuous manner.

It is to be understood that the foregoing description is merely exemplary and that in actual operations, pumps, heat exchanger, and other suitable equipment which are not illustrated on the drawing will be required. Distillation under reduced pressure, for example, particularly for the separation in fractionator 12, is contemplated and is desirable because of the increased tendency

for polymerization of the alkenylpyrrole as the temperature is raised. Because the boiling points of alkylpyrroles and the corresponding alkenylpyrroles are so close to each other, generally not differing by more than approximately 5° or 10° C., fractionating columns of great size (60 plates or thereabouts) are required and the period of sojourn in said columns is rather long. Consequently, for this reason also, it is desirable to maintain as low a distillation temperature as possible.

The following table illustrates the closeness of the boiling points of some of the known alkylpyrroles and corresponding alkenylpyrroles:

<i>Boiling points (°C.) of substituted pyrroles</i>	
N-ethyl	129-131°
N-vinyl	122°
2-ethyl	163-166°
N-propyl	145.5-146.5°
N-allyl	105°/48 mm.
2-propyl	176-179°
2-allyl	82-83°/24 mm.
2-(1,3-butadienyl)	198-199°

The foregoing boiling point ranges are those reported in the literature and are the limits within which all the reported samples boiled, that is, they are not the boiling range of any particular sample; N-ethylpyrrole, for example, has been reported to boil between 129° and 130° C. and also between 130° and 131° C. Generally the C-substituted derivative has a higher boiling point than the N-substituted derivative and the alkenylpyrrole a higher boiling point than the alkylpyrrole.

Preferably solid alkylation catalysts are used for the alkylation, particularly those which have a neutral or alkaline reaction. Granular gel catalysts of the silica-alumina type are preferred, although acid catalysts consisting of phosphoric acid or phosphorus pentoxide deposited on a granular solid supporting material are also suitable. Solid catalysts of this type may and preferably are used under vapor-phase conditions of operation and generally within the temperature range of approximately 400° to approximately 700° F. However, alkylation in the liquid phase at lower temperatures may be adopted with catalysts such as phosphoric acid, sulfuric acid, anhydrous hydrogen fluoride, and hydrogen fluoride containing boron fluoride. When using the latter acid catalysts, provision must be made for maintaining sufficient pressure to obtain liquid-phase reaction conditions and also for decomposing any acid compounds which are formed in the reaction. Thus, on alkylating pyrrole with ethylene in the presence of a large excess of hydrogen fluoride, some of the pyrrole will be converted to pyrrole hydrofluoride and perhaps ethylpyrrole hydrofluoride, although alkylation with ethylene at low temperatures favors formation of an N-ethylpyrrole, in which event, decomposition of such salts, generally by means of alkali, will be required before proceeding with the dehydrogenation thereof.

Suitable catalysts of the silica-alumina type are those prepared by subjecting partially dried silica gel to the action of a hydrolyzable salt of a metal of group III-B or IV-A of the periodic system. Such catalysts are described by Gayer (Industrial and Engineering Chemistry, 1933, volume 25, page 1122), Perkins et al. (U. S. Patent No. 2,107,710), McKinney (U. S. Patents No. 2,142,324 and 2,147,985), Fulton and Cross (U. S.

Patents No. 2,129,649; 2,129,732 and 2,129,733), Chapman and Hendrix (Serial No. 371,209, filed December 21, 1940), and Hachmuth (Serial No. 370,558, filed December 17, 1940). A suitable catalyst of this class may be prepared by precipitation of hydrous silica gel, by the addition of a sodium silicate solution to a solution of sulfuric acid. The resulting gel is washed with water and then partially dried. The partially dried silica gel is then washed again with water and treated with a solution of aluminum sulfate and again washed. The treatment with aluminum sulfate and washing with water are repeated until sufficient aluminum compound is adsorbed on the gel and the material is thereafter dried, preferably at a temperature not substantially in excess of approximately 225° F.

Catalysts suitable for the vapor-phase dehydrogenation of alkylpyrroles to alkenylpyrroles include chromium oxide and molybdenum oxide, which may be used alone or supported on suitable catalyst carriers. A preferred catalyst is unglowed chromium oxide supported on alumina or bauxite. Other suitable catalysts are thorium oxide on alumina. An especially advantageous catalyst is one containing chromium oxide together with calcium oxide or other alkaline-earth-metal oxide and/or an alkali-metal oxide or hydroxide, or one such as is described in Corson and Cox Patent No. 2,311,979. Other suitable chromium oxide catalysts are described in the patents of Morey and Frey (No. 2,270,887), Matuszak (No. 2,294,414), Grosse (No. 2,172,534), Huppke and Frey (No. 1,906,383 and 2,098,959), and Visser and Engel (No. 2,249,337).

The dehydrogenation is preferably conducted under reduced pressure. This may be accomplished by diluting the reactants with an inert gas such as nitrogen, steam, or carbon monoxide.

The temperatures which are used for the dehydrogenation are generally within the range of approximately 800° to approximately 1200° F. and preferably between 900° and 1100° F. As previously stated, low dehydrogenation temperatures may be used when catalysts are employed to facilitate the reaction.

The reaction mixture which is charged to the alkylator should contain a molecular excess of pyrrole over olefin. Preferred ratios are within the range of 3 mols of pyrrole to 1 mol of olefin to 6 mols of pyrrole to 1 mol of olefin. The particular ratio which is most suitable for use with a particular olefin will depend to a great extent on the reactivity of the olefin and the particular alkylation reaction conditions. With ethylene, for example, a higher molecular ratio of pyrrole to ethylene would be more desirable than with isobutylene.

As an example of the practice of the process of this invention, the following preparation of 2-vinylpyrrole, which is a batchwise operation, is cited: Pyrrole and ethylene are charged to a chamber containing a silica-alumina catalyst prepared according to the general method hereinabove described. The molecular ratio of pyrrole to ethylene is 5 to 1 and the materials are heated to such temperature that the temperature of the catalyst bed is approximately 500° F. The products are condensed and then fractionally distilled. The pyrrole (boiling range approximately 125° to 130° C.) is separated from the ethylpyrroles (boiling range approximately 130° to 165° C.), which probably includes N-ethylpyrrole and 2-ethylpyrrole.

75 Ethylpyrrole as obtained above is then heated

to a temperature of approximately 1000° F. by passing it through a tube and is then passed through a tube containing a chromium oxide catalyst supported on bauxite. The vapors are condensed and distilled fractionally in a 6-foot glass column packed with glass helices to separate the undehydrogenated 2-ethylpyrrole from the 2-vinylpyrrole.

Substantial yields of ethylpyrrole and 2-vinylpyrrole are obtained, although the conditions specified in the foregoing example are not to be understood to be optimum conditions.

In addition to 2-vinylpyrrole, the crude product from the reaction of pyrrole and ethylene contains vinylpyrroles in which the vinyl group is present on the nitrogen atom and on other carbon atoms of the pyrrole nucleus. Furthermore, when propylene and higher olefins are used as alkylating agents the product is a mixture of isomers in which the 2 or alpha alkenyl isomer is predominant and the 3 or beta alkenyl isomer is second in predominance, together with N-alkenyl-substituted pyrroles, although this will depend to a large extent on the specific reaction conditions used. It is not to be understood, therefore, that the invention is limited otherwise than as described or claimed.

2-vinylpyrrole and other alkenylpyrroles which can be obtained by the process of the present invention may be readily polymerized to products which are useful as plastics and which can be molded under heat and pressure and which are thermoplastic as contrasted to thermosetting plastic materials. They are also useful in the form of copolymers with 1,3-butadiene (erythrene), isoprene (2-methyl-1,3-butadiene) and piperylene (1,3-pentadiene), respectively, as "synthetic rubbers", namely products which possess a high elasticity and resemble natural rubber in other respects. Such copolymers even surpass natural rubber in some properties.

I claim:

1. A process for the production of an alkenylpyrrole which comprises alkylation of pyrrole with an olefin hydrocarbon to produce an alkylpyrrole and dehydrogenation of the resulting alkylpyrrole to an alkenylpyrrole.

2. A process as defined in claim 1 in which the olefin hydrocarbon is an olefin hydrocarbon having less than six carbon atoms per molecule.

3. A process for the production of an alkylpyrrole which comprises alkylation of pyrrole with an olefin hydrocarbon to produce an alkylpyrrole.

4. A process for the production of an alkenylpyrrole which comprises dehydrogenation of an alkylpyrrole.

5. A process for the production of an alkenylpyrrole which comprises alkylation of pyrrole with an olefin hydrocarbon in the presence of a solid alkylation catalyst at a temperature within the range of approximately 400° to approximately 700° F. to produce an alkylpyrrole and dehydrogenation of the resulting alkylpyrrole in the presence of a solid dehydrogenation catalyst at a temperature within the range of approximately 800° to approximately 1200° F. to produce an alkenylpyrrole.

6. A process as defined in claim 5 in which the alkylation catalyst is a catalyst of the silica-alumina type.

7. A process as defined in claim 5 in which the dehydrogenation catalyst is a catalyst containing chromium oxide.

8. A continuous process for the production of an alkenylpyrrole which comprises passing a mixture of an olefin hydrocarbon and pyrrole comprising pyrrole in molecular excess into contact with a solid alkylation catalyst at a temperature within the range of approximately 400° to approximately 700° F., recovering unreacted pyrrole and recharging it together with additional amounts of olefin hydrocarbon to the alkylation catalyst, separating alkylated pyrrole from the alkylation reaction product and subjecting it to dehydrogenation in the presence of a dehydrogenation catalyst at a temperature within the range of approximately 800° to approximately 1200° F., separating undehydrogenated alkylpyrrole from the product of the dehydrogenation reaction and recharging it to the dehydrogenation catalyst, and separating and recovering alkenylpyrrole from the product of the dehydrogenation reaction.

9. A process for the production of 2-vinylpyrrole which comprises alkylation of pyrrole with ethylene to produce 2-ethylpyrrole and dehydrogenation of the resulting 2-ethylpyrrole to 2-vinylpyrrole.

10. A process for the production of 2-ethylpyrrole which comprises alkylation of pyrrole with ethylene.

11. A process for the production of 2-vinylpyrrole which comprises dehydrogenation of 2-ethylpyrrole.

12. A process for the production of 2-vinylpyrrole which comprises alkylation of pyrrole with ethylene in the presence of a solid alkylation catalyst at a temperature within the range of approximately 400° to approximately 700° F. to produce 2-ethylpyrrole and dehydrogenation of the 2-ethylpyrrole in the presence of a solid dehydrogenation catalyst at a temperature within the range of approximately 800° to approximately 1200° F. to produce 2-vinylpyrrole.

13. A process as defined in claim 12 in which the alkylation catalyst is a catalyst of the silica-alumina type.

14. A process as defined in claim 12 in which the dehydrogenation catalyst is a catalyst containing chromium oxide.

15. A continuous process for the production of 2-vinylpyrrole which comprises passing a mixture of ethylene and pyrrole comprising pyrrole in molecular excess into contact with a solid alkylation catalyst at a temperature within the range of approximately 400° to approximately 700° F., recovering unreacted pyrrole and recharging it together with additional amounts of ethylene to the alkylation catalyst, separating ethylated pyrrole from the alkylation reaction product and subjecting it to dehydrogenation in the presence of a dehydrogenation catalyst at a temperature within the range of approximately 800° to approximately 1200° F., separating undehydrogenated ethylpyrrole from the product of the dehydrogenation reaction and recharging it to the dehydrogenation catalyst, and separating by fractional distillation in the presence of an inhibitor of polymerization and recovering 2-vinylpyrrole from the product of the dehydrogenation reaction.
